UNITED STATES PATENT OFFICE.

WILLIAM S. COOPER, OF PHILADELPHIA, PENNSYLVANIA.

DESIGN FOR A WATER-CLOSET BOWL.

SPECIFICATION forming part of **Design No. 20,520, dated February 17, 1891.**

Application filed January 5, 1891. Serial No. 376,792. Term of patent 14 years.

To all whom it may concern:

Be it known that I, WILLIAM S. COOPER, a citizen of the United States, and a resident of Philadelphia, Pennsylvania, have invented a 5 Design for a Water-Closet Bowl, of which the following is a specification.

My design for a water-closet bowl is fully shown in the accompanying drawing, which represents a perspective view of the bowl.

10 The bowl has a square back, rounded and contracted front, and tapering sides; but these are immaterial to the present design; the leading features of which are the ornamental band A, extending around the top of the 15 bowl, and the ornamentation B on the front of the bowl. The ornamental band A comprises a succession of scroll-like or cornucopia-shaped figures a and conventionalized floral figures b, overlapping portions of the 20 scroll-like figures, and the design for the ornamentation B on the front of the bowl comprises the central floral figure d, opposite upright leaf figures f, and scroll figures g, partially inclosing the floral figure d.

25 I claim—

1. The design for the ornamentation of a

water-closet bowl, said design comprising the front ornamentation consisting of the central floral figure, opposite upright leaf figures, and intermediate scroll figures, and the top band 30 comprising scroll-like figures and floral figures overlapping portions of the same, substantially as shown and described.

2. In a design for the ornamentation of a water-closet bowl, the design for the band 35 around the top, said design comprising a succession of scroll-like figures and floral figures overlapping portions of the same, substantially as shown and described.

3. In a design for the ornamentation of a 40 water-closet bowl, the design for the front ornamentation, comprising the central floral figure, opposite upright leaf figures, and intermediate scroll figures, substantially as shown and described. 45

In testimony whereof I have signed my name to this specification in the presence of two subscribing witnesses.

WILLIAM S. COOPER.
